[57] CLAIM

The ornamental design for a reclosable funnel fixture, as shown and described.

DESCRIPTION

FIG. 1 is a perspective view of a reclosable funnel fixture showing our new design;

FIG. 2 is a side elevational view thereof;

FIG. 3 is a rear elevational view thereof;

FIG. 4 is a top plan view thereof;

FIG. 5 is a bottom plan view thereof;

FIG. 6 is a vertical sectional view thereof taken along lines 6—6 of FIG. 4.

FIG. 1

FIG. 4

FIG. 2

FIG. 3

FIG. 5

FIG. 6
